UNITED STATES PATENT OFFICE.

CHARLES D. MATTISON, OF HASBROUCK HEIGHTS, NEW JERSEY.

CLOTH-CUTTING MACHINE.

SPECIFICATION forming part of Letters Patent No. 767,076, dated August 9, 1904.

Application filed December 26, 1902. Serial No. 136,540. (No model.)

To all whom it may concern:

Be it known that I, CHARLES D. MATTISON, a citizen of the United States, and a resident of Hasbrouck Heights, in the county of Bergen and State of New Jersey, have invented certain new and useful Improvements in Cloth-Cutting Machines, of which the following is a specification.

This invention relates to improvements in cloth-cutting machines of that class adapted for cutting a plurality of thicknesses of cloth at a single operation; and its main objects are to provide a cloth-cutter which can be directed easily without tiring the operator, to reduce the weight of the machine and the vibration of the working parts to a minimum without reducing the power used to operate the cutter and without sacrificing strength, and to mount the cutter in such a manner that its angular position can be changed instantaneously without appreciable effort to enable the cutter to follow closely the pattern-line along which the cloth is to be cut.

One of the principal features that distinguishes my improved cloth-cutter from others now in use is the mounting of the cutter and associated parts on a base in such a manner as to be capable of turning on said base in a horizontal plane without moving the base itself.

In carrying my invention into effect the stand by which the operating parts are usually supported is pivoted on a suitable base, a ball-bearing being preferably interposed between the base and the stand in order that the stand and the working parts carried thereon may turn on the base with the least possible friction.

In the preferred construction the stand supports a reciprocating or vibrating cross-head, to which the cutter is connected, this cross-head being connected with a rotary member by means of a crank connection. As it is important in machines of this type to keep the movements of the working parts in perfect balance, I make use of a second cross-head movable in the same path as the first, but in the opposite direction and preferably connected with the rotary member by a crank connection diametrically opposite the first,

and the use of these balanced cross-heads is 50 also one of the main features of the invention.

In addition to the features just described I employ a pair of cutting-blades capable of cutting piles of cloth of abnormal thickness, one of which blades has a shearing edge that 55 fills the slot in the base through which the cutter passes, and I also provide a manually-operable device for turning the main rotary member when the parts are on the dead-center and the main mechanism is ineffective. These 60 and other features of the invention not hereinbefore referred to are clearly illustrated in the accompanying drawings, in which—

Figure 1 is a front elevation of a cloth-cutting machine constructed in accordance with 65 my invention and showing the casing closed. Fig. 2 is a similar view with the casing open to illustrate the cutter and its operating and balancing mechanism. Fig. 3 is a sectional side elevation of the same. Figs. 4 and 5 are 70 enlarged sectional details of the independent manually-operated device for turning the main rotary member.

In carrying my invention into effect I provide a suitable base 2 of the usual circular type 75 having a sloping face to permit it to be shifted readily under a pile of cloth, and on this base I support a stand or post, such as 3, which carries the cutter and its operating mechanism. Instead of securing the stand to the 80 base in a fixed position, however, as is customary, I pivot the stand so that it can turn on the base in a horizontal plane, a ball-bearing being preferably interposed between these parts. In the present construction I have 85 shown a wide bearing which is formed by a cup 4 of considerable size, the upper surface of which is continuous with that of the base proper. This ball-cup has a ball-race of the usual type, between which and a complementary ball-race formed in the base a circuit of 90 balls is placed. The base 2, as shown, has a large central opening with an inwardly-projecting ring 5, the upper and lower faces of which constitute a pair of ball-races for the row of 95 balls before mentioned and for a second row of balls parallel therewith, these two sets of balls being indicated by 6 and 7. The balls 7

rest on an adjusting cap or washer 8, having a suitable race, and by means of this cap the bearing may be kept tight to prevent tipping of the stand on the base without impeding 5 the free horizontal oscillation of said stand.

The stand 3 is preferably a stiff steel bar securely fastened at its lower end in the ball-cup 4 and having a guide-slot 9, in which the cutter works. At its upper end this stand or 10 bar 3 supports the other movable and fixed parts of the machine. The principal working parts are a motor for transmitting power to the cutter and connections between this motor and the cutter. The motor proper is mounted 15 in this construction on a casing containing these intermediate connections, and the piston-rod of the motor, which is of the reciprocating type, extends through the top of the casing and is connected to the cutter-bar. The casing 20 is designated by 10 and at its under side is securely fastened to the upper end of the stand or bar 3, so as to be as rigid as possible in the plane of the force exerted.

The motor employed is preferably a compressed-air motor, because the maximum amount of power required for cutting a large number of thicknesses of cloth can be obtained from such a motor without increasing the speed of operation and without materially increasing 25 the weight of the machine by simply increasing the areas of the piston and its cylinder. This compressed-air motor is designated generally by 11 and is of a well-known type. Its piston-rod 12 is secured at its lower 30 end to a cross-head 13, which is mounted to slide up and down in the casing 10 between the inner side walls of said casing. The reciprocating or vibrating movement of this cross-head is here converted into a rotary motion 35 in the usual manner—that is to say, by means of a crank connection to a rotary member or shaft, such as 14. This rotary member here constitutes a crank-disk and has a pair of oppositely-disposed crank-pins 15 and 40 16, the former of which works in a guideway in the cross-head 13, while the latter moves in a similar guideway in a second cross-head 17, also vertically reciprocatory between the inner side walls of the casing. To the axis or 45 shaft proper of this rotary member a fly-wheel 18 is secured, and the slide-valves of the motor are controlled in the usual way by means of a strap-rod 19, connected with an eccentric secured to the rotary member. This fly-wheel 50 assures steadiness and regularity of movement of the cutter, and the balanced cross-heads 13 and 17 reduce the vibration of the machine to a minimum when the cutter is running at full speed.

55 The cutting member which I prefer to employ is in the form of a cutter bar or shank 20, having a pair of cutting-blades or cutters proper, 21 and 22, projecting therefrom. For cutting a pile of cloth of ordinary thickness

a single cutting-blade usually suffices; but 65 when the pile is of exceptional depth it is necessary to employ two cutters, one of which cuts the upper layers of cloth and the other the lower thicknesses. The upper blade may be of the ordinary construction; but the lower 70 cutter 22 preferably has at the heel of its cutting-surface a square shearing edge adapted to completely fill the cutter-slot in the ball-cup of the base. Loosely-woven materials frequently show frayed edges when severed 75 by an ordinary knife-edged cutter; but these threads are trimmed off by the square edge of the lower cutter at the point 23, and the result is a clean cut. This shear also keeps the cutter-slot in the ball-cup clear. 80

As a simple and convenient means for securing the cutter-bar in detachable connection with the cross-head 13 I have provided a clamping device (designated generally by 85 30) which coacts with an extension 13' of the cross-head for clamping the upper end of the cutter-bar in fixed connection therewith, the said clamping device in the present case being in the form of a screw-bolt, which is tapped or threaded into the cross-head, and the cutter-bar having an open-ended slot 14' in its rear side to receive the stem of said screw-bolt, on which it is adapted to be detachably retained between the clamping-surfaces formed by the head of the said screw-bolt and the adjacent cross-head. A lever-handle 30' on the 90 said screw-bolt serves as a means to turn or operate the same, and so enable the cutter-bar to be clamped and unclamped without the aid of a screw-driver or other similar tool, the open slot in the rear of the cutter-bar permitting the ready removal or replacing of the same subsequent to its release by the clamping device. As it is desirable that the lever-handle of the clamping device should turn 95 back in contact with the cross-head 13 when in normal clamping position, as in Figs. 2 and 3, I have secured the same in adjustable connection with the head of the bolt by passing one end around the said head in the form of a loop and clamping the same thereon by means of a screw 30''. This enables the clamping device to be adjusted for cutter-bars of different thicknesses. For instance, if the cutter-bar were removed and a thicker one substituted the lever-handle obviously could not 100 be turned back to the same position, and it would therefore be necessary to adjust the position of the lever on the bolt accordingly. 105

110 During the operation of a cloth-cutting machine the pile of cloth is usually held down by a presser-foot of suitable construction. In my improved machine I mount the presser-foot on a door 25, which closes the front of the casing 10 when the machine is in operation, 115 and this presser-foot may therefore be swung out of the way of the knife by swinging open this door. The presser-foot shown is design- 120

nated by 26, is properly slotted to permit the cutters to move therethrough, and is carried at the lower end of a slotted shank or bar 27, adjustable to any desired vertical position 5 and adapted to be clamped in place by a clamp-screw 28. This mode of mounting the presser-foot is a great convenience, as it permits the cutter-bar to be unclamped from the cross-head 13 without requiring a separate 10 operation for removing the presser-foot.

As is well known, the movement of the cutter in a machine of this type is occasionally checked by the stopping of the crank or cranks on the dead-center even though a fly-wheel is employed. In order to start the machine again 15 when this occurs, I have shown herein an independent manually-operated means for turning the rotary member of the machine to a point where the power mechanism will become effective to drive said member again. The means shown embodies a ratchet-wheel and a pawl and lever for turning the wheel. The fly-wheel in this case has ratchet-teeth cut in one side thereof and constitutes the ratchet-wheel. The 20 lever is pivoted at 32 at the back of the casing and is designated by 33. Said lever is divided at its end to receive a pawl 34, which is normally pressed toward the ratchet-teeth 31 by a spring 35. This pawl also has at its outer side 25 a cam-face 36, which co-operates with a fixed face or pin 37 on the casing, the parts being so organized that when the lever 33 is pushed down the pawl is pushed into engagement with the ratchet, while on the return of the lever to 30 its usual position by means of the spring 33' the pin 37 shifts the pawl away from the ratchet-wheel and holds it in an inoperative position while the power mechanism is operating properly.

Even under the most favorable conditions 35 the movement of the cutters is so rapid that they become heated, and it is desirable to employ some means for cooling them. For this reason I have shown at 40 a pipe leading from the exhaust-port of the motor and ending in a 40 Y, the arms 41 of which are so placed as to discharge the exhaust-air against the sides of the cutters and their guides and keep the same cool.

From the foregoing description it will be 45 seen that my improved cloth-cutter can be manipulated by means of the usual single handle 42 with but slight fatigue to the operator, because not only is the weight of the machine reduced to the minimum, but the work required to turn the device is similarly 50 reduced, the slightest touch being sufficient to turn the stand and the cutters on the ball-bearing of the base and keep the cutters close 55 to the line of the pattern.

What I claim is—

1. In a cloth-cutting machine, the combination with a rotary member and with means for rotating the same, of a pair of oppositely-dis-

posed crank-pins connected to said member, 65 a pair of oppositely - reciprocatory balanced cross-heads connected with said crank-pins, and a cutter secured to one of said cross-heads.

2. In a cloth-cutting machine, the combination with a base, of a stand pivoted to turn on 70 said base, a rotary member mounted on said stand, means for rotating said member, a pair of oppositely-reciprocatory cross-heads also supported on said stand and connected with said rotary member, and a cutter secured to 75 one of said cross-heads.

3. In a cloth-cutting machine, the combination with a base, of a stand pivoted to turn on 80 said base, a rotary member mounted on said stand, a motor also mounted on said stand, a pair of oppositely - reciprocatory balanced cross-heads also supported on said stand and connected with said rotary member, and a cutter secured to one of said cross-heads.

4. In a cloth-cutting machine, the combination with a base having a cutter-slot therein, 85 of a stand mounted on said base, a reciprocatory cutter mounted on said stand and having the heel portion of its cutting-surface formed with a square shearing edge which is movable 90 through the cutter-slot in said base.

5. In a cloth-cutting machine, the combination with a base having a cutter-slot therein, 95 of a stand mounted on said base and having cutter - guides, a reciprocatory cutter - bar mounted to slide between said guides, and a cutter carried by said cutter-bar in an operative position forward of the cutter-guides and having the heel portion of its cutting-surface formed with a square shearing edge movable 100 through the cutter-slot in said base.

6. In a cloth-cutting machine, the combination with a base, of a stand mounted on said base, a reciprocatory cutter mounted on said stand, a compressed-air motor also supported 105 on said stand and operatively connected with said cutter, and cutter-cooling means in communication with the exhaust - port of said motor.

7. In a cloth-cutting machine, the combination with a base, of a stand mounted on said base and supporting a casing, a door for said casing, cutter-actuating mechanism in said casing, a reciprocatory cutter movable through 115 said casing, and a presser-foot mounted on the front of and swinging with said door and having a cutter-guiding slot therein.

8. In a cloth-cutting machine, the combination with a base, of a stand mounted on said base, a reciprocatory cutter mounted on said 120 stand, a rotary member connected with said cutter, power-actuated means for turning said rotary member, and independent manually-operated means for turning said rotary member.

9. In a cloth-cutting machine, the combination with a base, of a stand mounted on said base, a reciprocatory cutter mounted on said

stand, a rotary member connected with said cutter, power-actuated means for turning said rotary member, a ratchet-wheel secured to said rotary member, and a pawl and lever 5 operative for turning said ratchet-wheel and normally out of engagement therewith.

10. In a cloth-cutting machine, the combination with a reciprocating cross-head, of a cutter-bar connected therewith and having an 10 open-ended slot to receive a part of the same, and a clamping device for securing the cutter-bar in detachable connection with the cross-head, for the purpose set forth.

11. In a cloth-cutting machine, the combination with a reciprocating cross-head, of a cutter-bar connected therewith, and a clamping device for securing the cutter-bar in detachable connection with the cross-head, said 15 clamping device having an adjustable lever-handle, for the purpose set forth.

12. In a cloth-cutter, a base formed in two parts, a circular center to which the standard

of the machine is connected, and an annular rim within which the circular center is revolvably secured, the division between the parts 25 extending through the base from its upper to its lower surface, substantially as described.

13. In a cloth-cutter, a base formed in two parts, a central part to which the standard of the machine is connected, and an outer part; 30 an annular ball-race formed between the two parts and balls therein so that the central part may turn on the balls; and a ring secured to the outer part and overlapping the inner part to hold the parts together when the central 35 part is lifted, substantially as described.

Signed at New York, in the county of New York and State of New York, this 23d day of December, A. D. 1902.

CHARLES D. MATTISON.
